UNITED STATES PATENT OFFICE.

FRANK HEDLEY, OF NEW YORK, N. Y.

ATTACHMENT FOR PREVENTING TELESCOPING OF CARS.

No. 867,367.

Specification of Letters Patent.

Patented Oct. 1, 1907.

Application filed December 10, 1906. Serial No. 347,057.

To all whom it may concern:

Be it known that I, FRANK HEDLEY, a citizen of the United States, residing in New York, county of New York, and State of New York, have made a certain new 5 and useful Invention in Attachments for Preventing Telescoping of Cars.

The invention relates to attachments for preventing the telescoping of cars in collision or other accidents.

The object of the invention is to provide an attachment 10 which is simple in construction, economical in manufacture and efficient in operation and which can be readily and easily applied to the ends of cars or of car platforms whereby the telescoping of the cars in case of collision or other accidents incident to their operation is guarded against.

A further object of the invention is the provision of simple, inexpensive and efficient means for preventing the relative vertical movement of adjacent ends of cars, in case of collision or similar accident, and which is usually 20 the antecedent of destructive, disastrous, and frequently fatal, telescoping of the cars.

A further object is to provide means for resisting the relative vertical movements of the adjacent ends of cars, in case of collision or accident, but which leaves 25 such ends free for vertical play in the ordinary operation of the cars under normal conditions.

A further object is to provide means for resisting any tendency of the cars to turn over sidewise in case of collision or other accident, without interfering with the 30 ordinary movements and vibrations of the cars while in operation under normal conditions.

Other objects of the invention will appear more fully hereinafter.

The invention consists substantially in the construction, combination, location and relative arrangement of parts, all as will be more fully hereinafter set forth, as shown in the accompanying drawing, and finally pointed out in the appended claims.

Referring to the accompanying drawing, and to the 40 various views and reference sign appearing thereon: Figure 1 is a broken view in top plan of a car platform showing the application thereto of an attachment embodying the principles of my invention. Fig. 2 is a front end view of the same. Fig. 3 is a broken view in 45 section on the line 3, 3, Fig. 1, looking in the direction of the arrows. Fig. 4 is a view similar to Fig. 3, on the line 4, 4, Fig. 2, looking in the direction of the arrows. Figs. 5 and 6 are views similar to Fig. 2, the end broken off, showing slightly modified forms of attachment embodying the principles of my invention. Fig. 7 is a view similar to Fig. 3, showing another slightly modified form of attachment embodying the principles of my invention. Fig. 8 is a diagrammatic plan view 50 showing the application of my invention to the ends of 65 freight or other cars which are not provided with platforms.

The same part is designated by the same reference sign wherever it occurs throughout the several views.

In case of collision or other accident of street or railway cars or trains, causing the ends of the cars to be 60 brought together with violent force, the danger is incurred of the cars telescoping the one upon the other, causing damage or destruction to the cars, and frequently injury and death to the occupants of the cars. In order to avoid the destruction and dangerous effects 65 of telescoping of the cars, it is a common practice to provide the under framing of the car bodies with sills or beams extending longitudinally of the cars, so that the strain imposed by the collision impact may be taken thereby, and, in the case of passenger cars, the platforms are constructed with a view to abut edgewise 70 against each other in case of collision, to resist the telescoping tendency. Experience has shown, however, that the force of the impact of the cars in colliding, frequently causes the end of one or the other of the cars to 75 be moved vertically, up or down, a distance sufficient for the platforms to pass by or to overlap the one upon or beneath the other, or the endwise extending sills or beams to be moved out of longitudinal alinement with each other. This condition is also contributed to by 80 the truck wheels of one or the other of the cars leaving the track rails, or the trucks or axles becoming broken or smashed by the impact of the collision, thereby causing the end of the car to be lowered relative to the proximate end of the adjacent car. In such cases, with 85 nothing to resist the force of the impact except the frail framing of the car vestibules, or of the ends of the car bodies, the ends of the cars climb the one upon the other, and crash into each other endwise, causing the dangerous and disastrous telescoping thereof. It has 90 been proposed to avoid these results and effects by providing the end of each car platform with means to mechanically engage the proximate platform of the adjacent car. Such method, however, is impractical and objectionable for the reason that thereby the 95 cars are not permitted to move freely with relation to and independently of each other, in the natural and normal operation of the train, and it is essential that this free independent movement of the cars vertically be provided for, and in turning sharp curves the engaging means, referred to, prevent the necessary flexibility 100 of the train for relative lateral movement of the cars, or else they become disengaged and hence are not at all times effective for the accomplishment of their objects and purposes. Moreover, by maintaining an engagement between the adjacent platforms of cars, which tend to resist the relative vertical play of the car ends under the influence of the swaying movements of the car body operating under normal conditions, the constant strains of such movements of the one car, and the 105 load imposed thereby, are distributed to the platform of the adjacent car, thereby causing the framing thereof 110

to be rapidly destroyed or injured. Again, in case of collision, it frequently happens that the force of impact, even when telescoping is avoided, causes the one car or the other to careen sidewise in a tendency to turn 5 over.

It is among the special purposes of my present invention to provide means which are exceedingly simple and easily applied wherein the free vertical and sidewise play of the cars in the normal operation thereof is 10 not interfered with, but which, in case of collision or other accident causing the ends of the cars to come together forcibly, and creating a tendency for the ends of the one car to slip or ride vertically past the adjacent end of the other car, will cause the ends of the cars, or 15 of the car platforms, to become interlocked, thereby not only holding the car body sills or platform ends in position to receive and resist the force of the impact, and, hence, preventing telescoping, but also resisting any tendency of one or the other of the cars turning over 20 sidewise.

In carrying out my invention I provide the ends of each car, or the ends of the car platforms, with a casting, forging, or plate, having bearing surfaces against which works corresponding surfaces of a similarly constructed and arranged casting, forging or plate, on the proximate end of the adjacent car or platform, in the normal operation of the cars, each casting, forging or plate, having recesses or seats and ribs or projections adapted to respectively receive or to be received in 25 corresponding ribs or projections and seats or recesses in the adjacent casting, forging or plate, in case of collision, when a sufficient relative vertical displacement of the car ends occurs, whereby the car ends become interlocked and held and maintained in such relative 30 positions as to prevent and avoid telescoping or turning over of the cars with the consequent disastrous if not fatal results.

In Figs. 1, 2, 3 and 4, I have shown my invention applied to the end of a car platform, reference sign A, 40 designating a portion of the car body, B, the platform and C, the casting, forging or plate. In this instance the end of the platform is recessed as at D, to receive the attachment, the outer surface of the latter lying flush with the facing E, of the platform end. The attachment is formed with the outwardly presenting ribs or projections F, having the intermediate seats or recesses G. The outer surfaces H, of the ribs form vertical bearing surfaces against which work the corresponding surfaces of the ribs or projections of the attachment 45 on the end of the platform of the adjacent car, in the normal operation of the cars, leaving each car end free for vertical as well as sidewise motion. In case of collision, however, and a consequent tendency of the ends of the platforms to ride up over the other thereby carrying 50 the surfaces H out of alignment, the ribs or projections F, of the one attachment are forced into the seats or recesses G, of the other, thereby causing the platform ends to become interlocked, and hence maintaining such platforms in such relative positions as to receive the force of the colliding impact, and hence preventing the telescoping of the cars, while at the same time resisting the tendency of one or the other of the cars turning over sidewise. The ribs or projections F, and the seats or depressions G, extend longitudinally of the 55 attachment, and, if desired, and in order to facilitate

the entrance of the ribs or projections into the seats or depressions, said ribs or projections may be formed with an outward taper, as shown. The castings, plates or forgings C, may be secured in place in any suitable or convenient manner, as, for instance, by bolts J. 70

Instead of the ribs extending the entire length of the attachment, one or more of them may be interrupted as indicated at F', in Fig. 5, and F'', in Fig. 6. I do not desire, therefore, to be limited or restricted in this respect, nor is my invention to be limited or restricted 75 to the number of the ribs or projections, nor to their relative arrangement. For instance, in Figs. 2, 3, 4, 5 and 6, three rows of ribs and two rows of seats are employed, while in Fig. 7, four rows of ribs and three rows of seats or depressions are employed. 80

It is obvious that my invention may be embodied in other forms and arrangements without departure from its spirit and scope, the essential feature being the provision of castings, forgings or plates on the ends of cars or car platforms which present vertically extending bearing surfaces to each other in the normal operation of the cars, permitting free vertical and lateral play or movement of the cars, but having ribs and seats or other engaging means adapted to interlock or engage with each other in case of collision when there is any 85 tendency of the ends of the cars or platforms to slide vertically upon each other a distance sufficient for the ribs or projections of one attachment to be brought into register with the seats or projections of the other opposed attachment, thereby holding the ends of the platforms, 90 or the longitudinally extending frame sills or beams, in alignment with each other and hence preventing the telescoping of the ends of the cars, the one upon the other, at the same time resisting any tendency of the one car or the other overturning sidewise. 95

In the case of freight or other cars which are unprovided with platforms, safety attachments embodying my invention may be readily applied to the ends of the deadwoods or bumpers with which the ends of such cars are usually provided, as indicated at K, Fig. 105 8, or the castings or forgings may themselves constitute and perform the function of deadwoods or bumpers, being suitably secured to the end-sills or other convenient part of the car body.

In using the term plate I desire to include thereby a 110 forging, casting or other suitable or convenient form of plate.

Having now set forth the object and nature of my invention and various forms and practical embodiments thereof, what I claim as new and useful, and of my own invention, and desire to secure by Letters Patent is:— 115

1. An attachment adapted to be secured to the end of a car or car platform, and having ribs or projections and seats or depressions in the outer surface thereof, the ends of the ribs or projections presenting vertical bearing surfaces. 120

2. An attachment adapted to be secured to the end of a car or car platform, and having outwardly extending ribs or projections, and intermediate seats or recesses in the outer surface thereof, the ends of the ribs or projections presenting vertical bearing surfaces, said ribs or projections extending longitudinally of the attachment. 125

3. An attachment adapted to be secured to the ends of a car or car platform, and consisting of a casting having ribs in its outer surface extending lengthwise thereof, 130 with seats or recesses intermediate said ribs.

4. The combination with a car and its platform said platform having a recess in the end thereof, of an attach- 135

ment adapted to be secured in said recess, and having ribs and seats in the outer face thereof.

5. The combination with a car and its platform, of an attachment adapted to be secured to the end of said platform, said attachment having ribs and seats formed in the outer face thereof, the outer edges of the ribs presenting vertical bearing surfaces.

6. An attachment adapted to be secured to the end of a car or car platform, and having ribs or projections and

seats or depressions formed therein, said ribs or projections 10 being outwardly tapering.

In testimony whereof I have signed my name to this specification, in the presence of two subscribing witnesses, on this 6th day of December, A. D. 1906.

FRANK HEDLEY.
